UNITED STATES PATENT OFFICE.

MARCUS P. EXLINE, OF DALLAS, TEXAS, ASSIGNOR TO ELBERT DUNLAP, OF DALLAS, TEXAS.

PASS-BOOK.

1,264,039.

Specification of Letters Patent. Patented Apr. 23, 1918.

Application filed August 26, 1914. Serial No. 858,712.

To all whom it may concern:

Be it known that I, MARCUS P. EXLINE, a citizen of the United States, residing at Dallas, in the county of Dallas and State of Texas, have invented certain new and useful Improvements in Pass-Books; and I do hereby declare the following to be a full, clear, and exact description of the invention, such as will enable others skilled in the art 10 to which it appertains to make and use the same.

This invention relates to pass books, and an object of the invention is to provide a cover having a recess in which is written 15 the name of the person owning the book, or any other name.

A further object of the invention is to provide a book cover so constructed that the owner's name will be written upon an integral part of the cover so that it will not be possible to remove the material carrying the name without destroying the book cover.

With these and other objects in view, the invention consists in features of construction and combinations of parts as will be hereinafter more fully described and claimed.

In the accompanying drawings

Figure 1 is a side elevation of my invention, and

Fig. 2 is a vertical section taken on the line 2—2 of Fig. 1 with the cover open and the body of the pass book in elevation in substantially the same position shown in Fig. 1.

Fig. 3 is a fragmentary vertical section through a modified form of the invention.

When pass books such as are used by bank depositors have been used for some time it is found that the name written on the outside 40 of the cover becomes worn away to such an extent that the name is frequently illegible. Heretofore it has been proposed to make pass books which would overcome this difficulty by providing an opening extending entirely through the cover of the book, but this weakens the cover to such an extent 45 that the same frequently breaks.

It has also been proposed as a means of avoiding the weakening of the cover just 50 mentioned, to subject a portion of the book cover to pressure, and thereby produce a panel sunken below the remainder of the surface for the reception of a name. But this last-named method is expensive, re-

quires special machinery, and generally is 55 not found to give the satisfaction expected.

The general aim of my present invention is to provide a pass book having the advantages of these books already mentioned but being free from the disadvantages inherent to said books.

To accomplish this result I take a pass book cover composed of an outer layer 1 of leather, stiffened paper, cloth, or any suitable material, which may be mounted upon 65 and stiffened by the backing sheet 2. The cover 1 is provided with an opening 3, which, as seen in Fig. 1, extends across the cover, and while shown approximately in the center thereof, is not necessarily so located.

The backing strip 2 is imperforate and covers the opening 3 in the layer 1.

Any suitable material may be employed for making the backing 2, and it is understood, of course, that the cover layer and backing are securely glued together or fastened in any other approved manner. A cover so provided may have secured thereto 75 the leaves 4 constituting the body of the 80 book.

The layer 1 is of substantial thickness, so that when the owner's or depositor's name is written on the face of the backing where exposed in the opening 3 so as to be visible 85 therethrough, the name will not be in contact with other papers or books carried in the owner's pocket. The backing 2, forming a vital part of the cover, cannot be mutilated without leaving a permanent defect 90 which could be noticed easily, such mutilation being caused, possibly, by an attempt to alter or remove the name from the backing 2.

The backing which carries the name also 95 stiffens the layer 1 so as to prevent the same from bending out of shape to leave the portion of the backing 2 exposed through the opening 3 to wear.

If the opening 3 should be found too wide 100 or too long it would be within the spirit of the present invention to make it smaller in either direction. It is apparent that the cover is only slightly weakened at the point where the name is written and at no place 105 is the cover as a whole perforated.

In order that the backing may serve as a suitable stiffening means, the same is made

co-extensive with the layer 1, and is made of such material as will receive ink.

It may be found desirable to have the writing surface upon which the name is to be written of a material more durable than the backing for the cover, and in this event I may employ a construction such as shown in Fig. 3. There is seen in this figure the backing 5 to which is secured a cover 6 having an opening therein indicated at 7 through which the pass book owner's name is to appear. Stretched across the opening is a strip of fabric 8, which has that side adjacent the backing secured to said backing and has the parts indicated generally at 9, which are under the cover 6, secured to said cover. This strip 8 may be of any material and dimensions and may extend the full width of the book or for a portion thereof. The strip is glued in place, after which the desired name may be written or printed on the same and be protected by the thickness of the cover, as already described in the first form of the invention described. 25 This latter construction gives a stronger cover and presents a writing surface which is less likely to wear.

What I claim is:

1. The herein described pass book comprising a series of entry leaves, and a flexible backing to which said leaves are attached comprising adhesively connected superposed co-extensive lining and cover members, the latter having a window, and the former having a portion of its area exposed through said window to the front of the book cover to receive suitable data. 20 35

2. In a pass book, a backing comprising an outer member and provided, in a portion forming the front of the book, with an opening, and an inner lining of pliable and non-porous material of substantially the same size as the outer member and secured thereto adhesively throughout adjacent faces, and a plurality of leaves secured to the inner member, the latter being exposed outwardly through said window for the reception of suitable data. 40 45

In testimony whereof I affix my signature in presence of two witnesses.

MARCUS P. EXLINE.
